UNITED STATES PATENT OFFICE.

FRANK D. PELLETIER, OF KANSAS CITY, MISSOURI.

DESIGN FOR AN ELECTRIC-LIGHT WALL-COSTUMER.

51,392.

Specification for Design.

Patented Oct. 16, 1917.

Application filed January 23, 1917. Serial No. 144,067. Term of patent 3½ years.

To all whom it may concern:

Be it known that I, FRANK D. PELLETIER, a citizen of the United States of America, and a resident of Kansas City, Jackson county, State of Missouri, have invented a new, original, and ornamental Design for an Electric-Light Wall-Costumer, of which the following is a specification, reference being had to the accompanying drawing, forming part thereof.

In the said drawing, Figure 1, is a front view of an electric

light wall costumer, embodying my new design.

Fig. 2, is a side view of the same.

Fig. 3, is a top plan view of the same.

I claim:

The ornamental design for an electric light wall costumer, as shown.

FRANK D. PELLETIER.

Witnesses:

G. Y. THORPE,

PERCY A. BUDD.
